(57) **CLAIM**

The ornamental design for a desktop display cord holder, as shown and described.

DESCRIPTION

FIG. 1 is a front perspective view of a desktop display cord holder;

FIG. 2 is a rear perspective view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a front elevation view thereof;

FIG. 8 is a rear elevation view thereof;

FIG. 9 is a front perspective view of a desktop display cord holder and showing in broken lines a representative secured cord and a representative design on the front of the desktop display cord holder;

FIG. 10 is a front perspective view of a desktop display cord holder and showing in broken lines a representative secured cord and an alternative design on the front of the desktop display cord holder;

FIG. 11 is a front perspective view of a desktop display cord holder and showing in broken lines a representative secured cord and another alternative design on the front of the desktop display cord holder;

FIG. 12 is a front perspective view of a desktop display cord holder and showing in broken lines a representative secured cord and another alternative design on the front of the desktop display cord holder;

FIG. 13 is a front perspective view of a desktop display cord holder and showing in broken lines a representative secured cord and a representative digital clock on the front of the desktop display cord holder; and,

FIG. 14 is a front perspective view of a desktop display cord holder and showing in broken lines a representative secured cord and a representative picture frame on the front of the desktop display cord holder.

The broken lines in FIG. 9 through FIG. 14 are for illustrative purposes only and form no part of the claimed design.

1 Claim, 7 Drawing Sheets
